PORTABLE PUMP ASSEMBLY

Raymond Hollis, Park Ridge, and Earl E. Scheibe, Northbrook, Ill., assignors to Graymills Corporation, Chicago, Ill., a corporation of Illinois

Filed Feb. 15, 1963, Ser. No. 258,750

5 Claims. (Cl. 222—324)

The present invention relates to portable motor-driven pumping assemblies of the type shown in Gray Patent 2,432,004, and more particularly to such assemblies wherein the motor may be readily connected and disconnected from the pump mechanism.

Although the present invention is particularly applicable for use in the printing industry where pumps are needed to supply ink to the presses for use, it can be understood that the invention is also useful wherever a sump contains fluid to be pumped and it is impractical or otherwise not feasible to clean the fluid each time the fluid is to be changed.

As presently practiced, in the printing industry when the color of the ink being fed to a printing press is to be changed, a separate ink container and pump assembly must be brought in for use. Each such container and pump assembly includes as a unit a container, a pump and a drive motor. With this type of construction, changing of the container requires changing of the pump assembly on each color change. Otherwise on each color change, the pump would have to be cleaned with solvent to remove all of the old color ink prior to using the pump with the new color. When a pump assembly of this type is to be cleaned, the pump container must first be fully emptied, after which the motor must be removed to allow the pump to be treated with suitable solvent for cleaning. If the motor is not disconnected and removed from proximity to the solvent, the motor bearings must be effectively shielded from contact with the solvent and its fumes due to the corrosive effect of the solvent. If the printing press is allowed to remain idle during this lengthy changeover, the time consumed during the changeover greatly increases the down time of the expensive printing presses now in use.

The present invention therefore has as an object to provide a pump assembly construction in which the drive motor for the pump can readily be connected to or disconnected from the pump without the necessity of use of any tools.

It is another object of the invention to provide a readily mountable and dismountable pump and motor assembly which allows a single motor to be used interchangeably with a number of pump assemblies.

The invention has as a further object to provide a simple and inexpensive coupling for joining the motor to the pump assembly which allows the motor to be removed readily from the pump assembly and which requires little adjustment and alignment for effecting the connection of the motor to the pump assembly.

It is a still further object of the invention to provide a pump assembly in which the coupling of the motor shaft to the pump shaft automatically positions a guard member to protect the motor and its bearings from contamination by solvent fumes and by ink spattered by the pump action.

It is still a further object of the invention to provide a portable pump assembly in which there is provided a readily disconnectible motor coupling which is adapted to receive a handled carrying member and pump shaft protector on removal of the motor. This carrying member allows the pump assembly to be carried about readily as required.

To effect these and other objects, the present invention utilizes a pump assembly in which the pump is suspended

2

from the lid of the container in which the fluid being pumped is stored. The pump has a drive shaft which extends through the container lid for connection to the drive motor. The motor is mounted on the lid on a base which is secured to the lid in a permanent manner. The base has manually manipulatable connecting members for effecting the motor mounting in a manner allowing the motor to be disconnected without the need of any tools.

The motor shaft is a hollow tube through which the pump shaft protrudes for coupling to the motor at a point above the motor. This coupling is completed by the use of a manually tightenable cap nut which locks an upper threaded and flatted end of the pump shaft to the motor shaft through an intermediate member flatted to receive the flatted shaft end and dogged for connection to the motor shaft, in a manner allowing coupling and decoupling of the shafts without the use of tools. In addition, this shaft coupling is inexpensive, takes up little valuable space below the motor and requires no bearings other than those used in the motor itself.

In assembling the motor on the pump assembly, the tightening of the shaft coupling serves to automatically draw a deflection plate carried by the pump shaft into a position adjacent to the bottom of the motor hollow shaft to shield the motor and its bearings from the intrusion of contaminants, and for the diffusion of vapors.

These and other objects as may hereinafter appear are attained in the embodiment of the invention shown in the accompanying drawings in which:

30 FIGURE 1 is a side elevational view partly sectioned of the pump assembly of the invention in its fully assembled condition;

FIGURE 2 is an exploded view of the upper end of the motor and the upper shaft coupling as used herein;

35 FIGURE 3 is a sectional view of the lower connection of the motor to the pump assembly in the disconnected state;

FIGURE 4 is a side elevational view partially sectioned of the pump assembly with the carrying handle and shaft

40 protector mounted to the assembly in place of the drive motor;

FIGURE 5 is a plan view of the pump assembly and motor mounting base; and

45 FIGURE 6 is a side sectional view of the pump assembly and motor connection revolved 90° from the showing of FIGURE 3, with the motor shown in side elevation to simplify the showing.

Continuing with the drawings and more particularly FIGURE 1, there is shown the container 10 which may be cylindrical in shape and which is adapted to store within it fluid such as ink to be pumped. The container has a circular opening 12 in its upper surface and this surface is covered by a circular lid 14. Lid 14 has a down-turned outer flange 16 extending about the outside of the container and the lid generally keeps fluid in the tank from being splattered or otherwise ejected from the container through opening 12.

Mounted on the lid is a mounting base 20 which is circular in shape and which is permanently secured to the lid. This mounting base includes a lower member 22 fitted within the container and an upper member 24 both circular in shape and coaxially mounted by suitable bolts to one another. These base members may be of cast iron or the like which is sufficiently strong to support the remainder of the assembly.

65 Suspending from the lower member 22 is the pump structure 26. This pump structure includes an outer tubular protecting column 28, the lower end of which is secured to the top of the pump housing 30. Within pump housing 30, there is rotatably mounted a centrifugal impeller 32. This impeller when rotated, drives fluid radially for flow up the discharge tube 34 which extends from

pump housing 30 upwardly through a suitable opening 36 in the lid for connection to the mechanism (not shown) in which the fluid is to be used. Impeller 32 is rotatably connected to pump shaft 38 which extends coaxially within vertically disposed tubular protecting column 28. The impeller is connected adjacent the bottom end of pump shaft 38. The bottom end 40 of shaft 38 is threaded below the impeller to accommodate a holding nut 42 abutting against the bottom of the impeller, locking the impeller to the shaft. Shaft 38 has a helical spring 44 fitted about the shaft and compressed between the top surface of impeller 32 and a suitable shoulder 46 on the shaft 38 to facilitate the mounting of the impeller on the shaft.

Pump shaft 38 extends vertically within tubular protecting column 28 and is pinned or otherwise connected in a permanent manner to a socket 52 within mounting base 20. Within the socket the pump shaft is permanently connected to a drive shaft 54 which extends vertically through a clearance opening 55 in mounting base 20 and continues its vertical extent axially through a drive motor 56. The socket connection allows a limited amount of relative movement of the shaft 54 both axially and gyroscopically. The uppermost end 58 of drive shaft 54 is threaded and has opposed flats for coupling the drive shaft to the motor as will be described more fully.

The upper base member 24 as shown best in FIGURES 3, 5 and 6 is circular in shape and mounted to the top surface of lid 14. This member 24 which may be a unitary casting, comprises a lower plate 62 resting on the lid and an upper plate 64 spaced from the lower plate by integral reinforcing beams 66. These reinforcing beams are concentrically positioned within the upper base member and are spaced adjacent the base member periphery. Angularly spaced from these beams are two motor mounting members 70 which are mutually spaced apart by 180 degrees. Each member includes a stud 72, the upper section of which is threaded. The lower section of each stud is unthreaded, and fits within a clearance opening 74 in the lower plate 62. Each lower section is hollowed to receive a compression spring 75 bottoming against a lower wall of the opening, with the spring urging the stud upwardly through clearance opening 76 past the top surface of the upper plate 64. About the center of the stud there is affixed by any suitable means such as by set screw, a large knurled thumb knob 78 the diameter of which is considerably greater than the diameter of the adjacent opening 76. A compressible rubber bellows 79 protectively encloses the lower section of the stud between the knob and the top surface of plate 62. Spaced at 90 degrees from each of the members 70 about the periphery of the top plate 64 are two locating holes 80.

The drive motor 56 is cylindrical in shape with its circumference virtually the same size as the circumference of upper mounting base plate 64. This motor has a central tubular opening 82 extending axially through it and about this opening the motor has a tubular drive shaft 54. Opening 82 is sufficiently large to allow pump drive shaft 54 to freely extend therethrough without interference of the drive shaft with rotation of motor shaft 84. In its lower surface 86, motor 56 includes two spaced apart locating pins 88 protruding from the surface and positioned to fit within locating holes 80 to guide the motor into the proper alignment on mounting base 20. Lower surface 86 of the motor further includes two spaced apart tapped openings 90 each positioned to receive in a mating and locking relationship the upper end of a stud 72. In connecting the motor to base 20, pins 88 are fitted within locating holes 80 to position the motor on the mounting base and studs 72 are tightened into a locking engagement with tapped holes 90 by manual tightening of the thumb knobs 78. The knob tightens against the upper plate 64 of the mounting base and lock the motor 56 to the base 20.

To drivingly couple the drive shaft 54 to the motor

shaft 84 there is utilized a readily detachable upper end coupling 92 (shown best in FIGURE 2) which will now be described. This upper end 94 of the motor shaft terminates a short distance below the threaded end 58 of drive shaft 54. At its upper end 94, motor shaft 84 has formed or cut therein a diametric slot 96 of limited depth. An internally flattened driving tube 100 of approximately the same diameter as motor shaft 84 is fitted on shaft end 94 and this tube has downwardly directed driving detent arms 102 shaped to fit within slot 96. To lock the coupling of shafts 54 and 84 together, a knurled knob 104 tapped internally to receive shaft threaded end 58 is fitted over drive shaft 54 and tightened down on tube 100 to lock the positive connection between the flattened, threaded shaft end 58 and the internally flattened tube 100. The interior of knob 104 is recessed with an opening 106 in its bottom surface, this opening being in communication with an interior tapped opening 108 in knob 104, the tapped opening sized to receive threaded shaft end 58.

With the coupling construction set out, once the motor has been mounted on base 20 and tightened thereon by mounting members 70, the driving tube 100 is fitted on drive shaft 54 and the detent arms 102 are mated with slot 96. The knurled knob is then tightened on the threaded, flattened end 58 of drive shaft 54 until the inner shoulder 110 which forms the upper surface of recessed opening 106 bears against the top of driving tube 100 tightening against it. This tightening action tends to raise pump shaft 38 an amount limited by the axial movement permitted by socket 52. Finally, knob 104 is tightened sufficiently to lock the positive driving relation between the two shafts 54 and 84. A suitable cup-shaped safety cup 112 may fit over handle 104 and be held frictionally by a suitable shoulder on the motor upper surface for the purpose of protecting the threaded coupling from the effects of fluids.

To utilize the lifting effect on the shafts resulting from the tightened shaft coupling, drive shaft 54 has secured about it a series of deflector plates (shown best in FIGURES 3, 5 and 6) adjacent the upper plate 64 of mounting base 20. The lowest of these circular deflector plates 120 may be fabricated of material such as Teflon or other suitable compliant material which will not be readily corroded. Deflector plate 120 may rest on a suitable shoulder on the drive shaft 54 and has spaced thereabove a second disc or circular plate 122 which may be metal. These circular plates are considerably greater in circumference than the circumference of shaft opening 82 in the bottom of motor 56 and motor shaft 84. These washers or plates will ride up with shaft 54 on tightening of the drive coupling to a position adjacent the bottom of motor 56 and will deflect all randomly spattered ink solvent or fumes from reaching the motor shaft and bearings internal to the drive motor. Thus, tightening of the coupling positions these deflector plates adjacent the bottom opening in motor 56 and thereafter these plates will guard the motor interior from the intrusion of contaminants.

From the foregoing explanation it can be seen motor 56 is connected to the pump assembly by manually operable members such as mounting members 70 and coupling members 92. To detach the motor, knob 104 is loosened and removed along with driver tube 100 once safety cap 112 has been removed. This release allows shaft 54 to drop a short distance up to the amount limited within socket 52. A suitable thread protector 124 which is internally tapped may be screwed on to threaded end 58 to prevent thread damage in handling. Next, thumb knobs 78 are loosened to loosen the mounting to base 20 and motor 56 may be lifted vertically up drive shaft 54 until opening 82 clears the threaded top of shaft 54. Handle 126 is connected to suitable motor secured brackets 128 to allow the motor to be carried away easily.

For handling of the pump assembly and container once the motor has been removed, a tubular protector 130

(shown best in FIGURE 4) is placed on the mounting base. The bottom part of this protector has a frame 132 which may be a metal casting the bottom surface of which is configured similarly to bottom surface 86 of motor 56. Thus frame 132 has locating pins (not shown) registering with locating openings 86 and tapped holes 134 shaped to receive in locking engagement studs 72. Frame 132 naturally has a central opening 136 sufficiently large to freely accommodate drive shaft 54. Extending rigidly upwardly from the frame 132 and secured thereto is an outer tube 138 extending vertically past the top of the drive shaft. This tube of sheet metal or the like surrounds the shaft with sufficient clearance distance so that the tube does not come into contact with threaded end 58 of the drive shaft. Optionally as shown in FIGURE 4, thread protector 124 is screw onto to threaded end 58 to additionally protect those threads from damage. Secured to the upper portion of tube 138 is a configured carrying handle 142 which is shaped to allow the handle to be grasped for carrying the pump assembly and container.

When the motor is to be replaced on the pump assembly following pump cleaning, protector 130 is removed by loosening mounting members 70 and removing the protector 130 upwardly to clear shaft 54. Motor 56 is raised above the drive shaft 54 and slipped over the shaft. The motor is lowered until locating pins 88 contact the upper surface of plate 64. The motor is rotated slowly until the pins register with locating openings 86 in mounting base 20 and the motor is lowered to rest on base 20. Thus the only alignment necessary in this mounting is the angular movement of the motor leading to registry of the locating pins and locating holes. Studs 72 are then tightened manually by thumb knobs 78 to lock the motor on the base securely. Thread protector 124 is then removed and coupling 92 is secured in place with tube 103 and knurled knob 104. Knob 104 is tightened raising the shaft and deflector plates and the completed assembly is ready for use.

While there has been described what is at present thought to be a preferred embodiment of the invention it will be understood that modifications may be made therein and it is intended to cover in the appended claims all such modifications as fall within the true spirit and scope of the invention.

What is claimed is:

1. Portable pumping apparatus comprising a container adapted to bear fluid, a lid therefor, a pump suspended from the underside of said lid for positioning within the container below a fluid level when the lid is in a closed position, a drive shaft extending from the pump through the container lid, a base member mounted on said lid, means connecting said base member to a drive motor, a drive shaft on said motor adapted to be coupled to said pump drive shaft, said connecting means including a plurality of readily disconnectible linkages for releasing the connection of the drive motor to said base member on manual manipulation thereof for disassociation of the drive motor therewith, a container carrying member, means in said carrying member receptive of said disconnectible linkages to secure said carrying member to said base member, a hollow tube in said carrying member extending beyond the end of said pump drive shaft to fully accommodate therein said pump drive shaft in an enclosed manner, and a carrying handle on said carrying member to allow said container to be lifted and carried about.

2. Portable pumping apparatus comprising a container, a lid therefor, a pump suspended from the underside of the lid for positioning said pump within the container below the fluid level when the lid is in the closed position, a base member mounted on said lid, a drive shaft extending from said pump through the container lid and

5 through the base member, a motor mounted on said base member with the motor drive axis coaxial to the drive shaft of said pump, a hollow rotatable drive shaft in said motor accommodating therein said pump shaft, means coupling said motor shaft with said pump shaft for joint rotation, said coupling means including a tightening member connected to said pump shaft for drawing said pump shaft axially through said motor shaft during said connection, and guard means responsive to the axial drawing of said pump shaft for movement therewith to a position adjacent said motor shaft to deflect liquid ejected from said container from said motor shaft.

3. An apparatus as claimed in claim 2, in which said guard means comprises a plurality of annular spaced plates mounted on said pump drive shaft and movable therewith axially and rotatably.

4. A portable pumping apparatus for use in a container having a lid comprising, in combination, an upper base member positioned on the upper side of the lid, a lower base member positioned adjacent to the lower side of the lid and fixed to the upper base member to fix said members to the lid, a pump supported by the lower base member and being positionable in the container, a motor removably mounted on said upper base member, a plurality of studs mounted in the upper base member and threadedly engagable with the motor to secure releasably the motor to the upper base member, said motor having a hollow rotatable drive shaft, a pump drive shaft drivingly connected to the pump and rotatably extending through the lid and through the hollow rotatable drive shaft, and a connector positioned adjacent to the motor on the side opposite the pump engaging the pump drive shaft and the hollow rotatable drive shaft for releasably connecting said shafts.

5. A portable pumping apparatus for use in a container having a lid comprising, in combination, an upper base member positioned on the upper side of the lid, a lower base member positioned adjacent to the lower side of the lid and fixed to the upper base member to fix said members to the lid, a pump supported by the lower base member and being positionable in the container, a motor removably mounted on said upper base member, a plurality of studs mounted in the upper base member and threadedly engageable with the motor to secure removably the motor to the upper base member, a knob secured to each of the studs for manipulating the respective studs, said motor having a hollow rotatable drive shaft, a pump drive shaft having one end drivingly connected to the pump and the other end extending through the lid and through the hollow rotatable drive shaft, said pump drive shaft having a flattened portion on the end extending through the hollow rotatable drive shaft, a detent mounted on the flattened portion of the pump drive shaft and drivingly engagable with the hollow rotatable drive shaft to provide a driving connection between the shafts, and a cap mounted on the pump drive shaft for holding the detent in driving connection with the hollow rotatable drive shaft, whereby the motor is readily disengagable from the pump by removal of the cap and the detent to disengage the shafts, and the studs are disengaged from the motor to release the motor from the upper base member.
